UNITED STATES PATENT OFFICE.

HENRY J. GILBERT, OF SAGINAW, MICHIGAN, ASSIGNOR TO NATIONAL WASHBOARD COMPANY, OF CHICAGO, ILLINOIS, A CORPORATION OF WEST VIRGINIA.

WASHBOARD.

1,283,148.

Specification of Letters Patent. Patented Oct. 29, 1918.

Application filed January 18, 1916. Serial No. 72,730.

To all whom it may concern:

Be it known that I, HENRY J. GILBERT, a citizen of the United States, residing at Saginaw, in the county of Saginaw and State of Michigan, have invented certain new and useful Improvements in Washboards, of which the following is a description, reference being had to the accompanying drawings, forming a part of this specification.

My invention has for its object the provision of a novel and improved soap-rest or support for washboards, of simple and cheap but advantageous construction, and the combination of such soap-rest with the frame and rubbing surface of the washboard in a simple and efficient manner, all as hereinafter set forth and more particularly pointed out in the claims.

- 20 In the accompanying drawings Figure 1 is a perspective view of the forward side of the washboard embodying my invention; Fig. 2 a similar view of the rear side of the same washboard, provided with a support for the rubbing surface in the form of a thin wooden back; Fig. 3 a view corresponding to Fig. 2 but showing the support for the rubbing surface in the form of truss-rods; Fig. 4 a vertical section of the washboard on the dotted line 4—4 of Figs. 1 and 2; Fig. 5 a corresponding view of the construction shown in Fig. 3; Figs. 6 and 7 enlarged details, respectively, of the construction at the top and bottom cross-bars of the washboard shown in Figs. 1, 2 and 4; Figs. 8 and 9 enlarged details, respectively, of the construction at the top and bottom cross-bars of the washboard shown in Figs. 3 and 5; Fig. 10 a perspective view of the soap-rest shown in Fig. 1 and in section in Figs. 4 and 6; Fig. 11 a perspective view of a similar soap-rest of slightly modified form; Fig. 12 a perspective view of a similar soap-rest in still another slightly modified form; Fig. 13 a similar view of another modified form of soap-rest; Fig. 11^a a cross-sectional detail of a double soap-rest adapted for use in double-sided washboards; Fig. 12^a a similar view of a double soap-rest, for the same purpose, of slightly different form; Fig. 12^b a front view of one of the notches of the form shown in Fig. 12, and Fig. 12^c a front view of a wider notch of similar form.
- 55 The same letters of reference are employed to indicate corresponding parts in the several views.
- The rectangular frame of the washboard, composed of the side-bars A and B, and the top cross-bar C and bottom cross-bar D, may be of the usual or any suitable construction. The intermediate cross-bar E, which constitutes the support and connecting medium for the bottom of the brand-board F and the top of the metal rubbing surface G and its supporting back H, and whose forwardly projecting portion E' constitutes the soap-rest for supporting the cake of soap when not in use, is of novel and improved construction. It is seated at its opposite ends in suitably shaped recesses in the side-bars A and B of the washboard frame, and in the construction shown is provided in its upper side with a longitudinal groove a, in which fits the lower edge of the brand-board F, as best shown in Figs. 4, 6, and 10 to 13, and in its lower side with a longitudinal groove b in which fits the upper edge of the supporting back H for the rubbing surface G. The under side of this cross-bar E is preferably shaped as shown, the bottom portion of the bar, in front of what would otherwise be the lower half or portion of the deep groove b, being cut away about midway of the height of such groove, to form a downwardly facing horizontal surface or shoulder c. The upper edge of the supporting back H is provided with a deep groove d extending transversely from side to side of the washboard, and this groove divides the upper edge of the back H into two vertically projecting portions, the rear one of which constitutes a tenon e, which fits into the groove b in the cross-bar E, and the forward one of which constitutes a support f for the upper end of the metal rubbing surface G. The upper portion of the metal rubbing surface G is bent rearwardly and then downwardly, forming a hook-shaped portion, which hooks over the upper edge of the support f, and is clamped and confined between the upper edge thereof and the under surface c of the forward portion of the cross-bar E, thus forming a secure fastening for the upper end of the rubbing surface G. The rear side of the cross-bar E, at the right of the groove b, in the present instance and preferably, extends downwardly and fits against the rear side of the back H for a considerable distance below the horizontal

plane of the upper end of the rubbing surface G and its support f, and the upper and lower corners of the back of the bar E are also preferably rounded off or curved as 5 shown.

The connection of the bottom of the back H with the lower cross-bar D of the washboard frame in the construction shown is similar to that of the connection of its upper 10 per end with the cross-bar E, the back H being provided in its lower edge with a groove d', Fig. 7, similar to the groove d in its upper edge, forming a tenon e' fitting in a groove b' in the cross-bar D, and a 15 shorter portion f' in front of the groove d', around the lower edge of which portion f' the lower end of the rubbing surface G is hooked, and between which and the upper surface c' of the forward part of the cross-bar D it is confined, as shown.

The side edges of the brand-board F preferably fit in vertical grooves formed in the inner sides of the side bars A and B of the washboard frame, while its upper edge fits 25 in a horizontal groove in the under side of the top cross-bar C of the frame. The brand-board F is thus surrounded by and snugly inclosed within the side bars A and B and the top cross-bar C and intermediate 30 cross-bar E, and constitutes, when the washboard is in the inclined position usually occupied by it when in use, the bottom of a completely inclosed rectangular soap-receptacle, of which the side bars A and B constitute 35 the side walls, and the top cross-bar C and intermediate cross-bar E the top and bottom walls, respectively.

As heretofore stated, the forwardly projecting portion E' of the cross-bar E in front of the brand-board F constitutes the soap-rest of the washboard for which purpose it preferably has a flat and substantially horizontal upper surface a and a downwardly and rearwardly inclined forward surface b the surfaces a and b joining each other at an acute angle at the upper forward corner c' of the soap-rest and the downwardly and rearwardly inclined surface b terminating at its lower edge approximately coincident with the upper end 50 of the front face of the rubbing surface G, and in about the same vertical plane.

For the purpose of affording ready escape of water from the soap-receptacle 55 above the soap-rest E forwardly over the front of the rubbing surface G of the board I provide the soap-rest E with a plurality of drainage notches or openings forming downwardly and forwardly inclined drain 60 passages from the face of the brand-board F through the soap-rest E', to and over the front of the rubbing surface G. These drainage notches or openings preferably take the form of the open notches best 65 shown in Figs. 1, 10 and 11, where it will be

seen that each notch E² is so cut or formed in the soap-rest E' as to provide a flat inclined rear wall a², and opposite parallel side walls b² projecting forward from the rear wall a², at right angles thereto. To 70 remove the sharp corners or points which would otherwise be formed at the forward extremities of the side walls b² of the notches E² the forward corner of the soap-rest E' is beveled off at its points of junction 75 with the side walls of the notches, as at c².

The notches E² are preferably made of such width, say half an inch or slightly more, as to readily permit the upward passage of one's finger through them, which 80 is also facilitated by the beveling off of the corners of the notches at the points c². This enables the cake of soap resting upon the upper surface of the soap-rest E' over any one of the notches E² to be readily lifted by 85 passing the finger upward through the notch and engaging it with the underside of the soap. The beveling off of the corners of the notches also prevents the clothes which are being washed from catching upon 90 and being injured by them.

I preferably employ at least four of the drainage notches E² in the soap-rest E', as shown in Figs. 1 and 10 both to facilitate the drainage of water from the brand-board 95 surface above the soap-rest and also to enable the cake of soap to be the more readily engaged by the finger of the user of the washboard, passed up through one of the notches E², wherever the cake of soap may 100 happen to be left transversely on the soap-rest; but the advantages of this feature of my invention may be utilized, to a greater or less degree, with a less number of such notches, as for instance with two, as shown 105 in Fig. 11.

Again, while drainage notches of approximately the form shown in Figs. 1, 10 and 11 possess advantages over those of other forms which I have employed, the advantages of my invention may be utilized to some degree with drainage notches of other forms such as those shown at E² in Fig. 12 for instance, or even with inclined drainage holes extending diagonally downward and forward through the soap-rest E', as shown at E⁴ in Fig. 13. The number of notches shown in Fig. 12 and the number of holes shown in Fig. 13 may be increased with advantage as in the case of the notches 110 shown in Figs. 10 and 11. In Fig. 12^b I have shown a front view of one of the notches of the form illustrated in Fig. 12, to better exhibit the shape of such notch, and in Fig. 12^c I have shown a wider form 115 of a similar notch, which is in some respects preferable to that shown in Figs. 12 and 12^b.

In the foregoing description I have referred to the supporting back H for the rubbing surface G as a single element or mem- 120

ber of the general construction of the washboard shown in Figs. 1, 2, 4, 6 and 7, but as shown in Fig. 2 said supporting back in practice is formed of a plurality of vertically disposed members h , preferably consisting of thin wooden boards as usual, which members are also preferably slightly separated from each other at their adjacent edges, to leave open spaces h' between them, and further provided in their lower portions with vertical slots h^2 , the provision of such open spaces h' and slots h^2 being for the purposes of ventilation.

While some of the features of my invention above described relate to and are dependent upon the employment of a supporting back for the rubbing surface of the general form and character of that disclosed in Figs. 2, 4, 6 and 7 and above described, the features of my invention which relate to my novel and improved soap-rest E' are not in any way dependent upon the employment of a support for the rubbing surface in the form of the thin wooden back H , but on the contrary may be employed in washboards having a different form of support for the rubbing surface, such, for instance as the truss-rod form of support shown in Figs. 3, 8 and 9. In the construction shown in these last mentioned figures, the rubbing surface G of the washboard is supported against the downward and backward pressure exerted upon it in use by a plurality of vertically disposed truss-rods J , in the present instance five in number, which are secured at their upper ends in the cross-bar E of the framework of the board and at their lower ends in the cross-bar D thereof, as shown in said figures of the drawings. Under this construction the upper and lower ends of the back-support for the rubbing surface do not coöperate with the upper and lower cross-bars in securing the upper and lower ends of the rubbing surface itself in place, but on the contrary the upper and lower ends of the rubbing surface are simply suitably disposed to enter and be confined in inclined grooves g , g' formed for their reception in the cross-bars E and D , respectively, as shown in Figs. 8 and 9.

It will be further understood that the features of my invention which relate to my novel and improved soap-rest may be also employed with advantage in double-faced washboards, or washboards having rubbing surfaces on their opposite sides, my novel soap-rest E' being simply duplicated, in such instance, upon both sides of the cross-bar E , instead of being employed only on the forward side thereof, as in the constructions shown in the figures of the drawings which have been so far referred to and described. In Fig. 11^a I have shown a vertical cross-sectional detail of one form of cross-bar and double soap-rest for such double-

sided washboard, the sectional view being taken through a pair of the opposing drainage notches E^2 , and in Fig. 12^a I have shown a similar cross-sectional detail of another slightly differing form of cross-bar for such double-sided boards, provided with like oppositely disposed soap-rests and drainage notches. The cross-bar shown in Fig. 11^a is adapted for use in what are commonly termed "solid zinc" washboards, meaning thereby washboards having opposing rubbing surfaces formed on the opposite sides of a single heavy sheet of zinc or other metal, the upper edge of which heavy sheet of metal will fit and be confined in the narrow groove a^2 in the under side of the cross-bar shown in Fig. 11^a, and the lower end of such single sheet of zinc being curved around and held by the metal cross-rod constituting the lower member of the frame of such washboards, as usual. The cross-bar shown in Fig. 12^a, on the other hand, is adapted for use in double-sided washboards in which the opposing rubbing surfaces are formed of separate sheets of zinc or other metal, which are supported by an interposed "lining" of thin wooden boards, somewhat similar to the back H of the single-sided board shown in the present drawings and hereinbefore described. In these last mentioned double-sided boards the upper edges of the zinc rubbing surfaces are curved and overlapped upon each other on the upper edge of such supporting "lining," and the latter, with the interposed curved portions of the rubbing surfaces, fits and is confined within the concave groove or recess a' formed in the under side of the cross-bar E , the lower end of the "lining" and the lower ends of the rubbing surfaces being similarly confined in a concave groove or recess formed in the upper side of the lower wooden cross-bar of the framework of the washboard, as usual in such boards. The groove a in the upper side of the cross-bar in both Figs. 11^a and 12^a is for the reception of the lower end of the brand-board F , as in the construction shown in Figs. 1 to 8.

Having thus fully described my invention, I claim:

1. In a washboard, the combination, with the washboard frame comprising the side bars A and B and top and bottom cross-bars C and D , of the intermediate cross-bar E provided in its under side with the longitudinal groove b and formed at its forward side into the projecting soap-rest E' , the brand-board F forming with the side bars A and B and cross-bars C and E a closed-bottom soap-receptacle above the soap-rest E' , the drainage from which all flows forward over the rubbing surface of the board, the supporting back H provided in its upper and lower edges with the grooves d and d' forming vertically projecting tenons e and e' at

one side of said grooves and vertically extending supports f and f' at the opposite side thereof, said tenons e and e' fitting in the longitudinal groove b in the under side 5 of the cross-bar E and in the similar groove b' of the cross-bar D, respectively, and the sheet metal rubbing surface G having its upper end hooked over and confined between the support f and the surface c on the under 10 side of the cross-bar E, and having its lower end hooked under and confined between the support f and the surface c' on the upper side of the cross-bar D; substantially as described.

15 2. In a washboard, the combination, with the side bars A and B, and top cross-bar C of the intermediate cross-bar E formed upon one side with the forwardly projecting soap-rest E' having a plurality of downwardly 20 and forwardly inclined drainage passages, and the brand-board F, forming with the side bars A and B and cross bars C and E a closed-bottom soap-receptacle above the soap-rest E', the drainage from which flows 25 downwardly and forwardly through the inclined passages in the soap-rest and over the rubbing surface of the board; substantially as described.

3. In a washboard, the combination, with 30 the side bars A and B, and top cross-bar C, of the intermediate cross-bar E formed upon one side with the forwardly projecting soap-rest E' having a plurality of downwardly and forwardly inclined open drainage notches, and the brand-board F forming 35 with the side bars A and B and cross bars C and E a closed-bottom soap-receptacle above the soap-rest E', the drainage from which flows downwardly and forwardly through the inclined open drainage 40 notches and over the rubbing surface of the board; substantially as described.

4. In a washboard, the combination, with the side bars A and B, and top cross-bar 45 C, of the intermediate cross-bar E formed upon one side with the forwardly projecting soap-rest E' having a plurality of downwardly and forwardly inclined open drainage notches E² having flat bottoms a² and 50 approximately parallel opposing side walls b² terminating at their forward ends in the beveled surfaces c², and the brand-board F forming with the side bars A and B and cross-bars C and E a closed-bottom soap-

receptacle above the soap-rest E', the drainage from which flows downwardly and forwardly through the inclined open drainage notches E² and over the rubbing surface of the board; substantially as described.

5. In a washboard, the combination, with the side bars A and B and top cross-bar C, of the intermediate cross-bar E provided in its upper side with the longitudinal groove a and formed upon one side with the forwardly projecting soap-rest E' having a plurality of downwardly and forwardly inclined drainage passages, and the brand-board F surrounded by and having its four edges fitting in grooves in the side bars A and B and the top cross-bar C and intermediate cross-bar E, to form a closed-bottom soap-receptacle above the soap-rest E', the drainage from which flows downwardly and forwardly through the inclined drainage passages and over the rubbing surface of the board; substantially as described.

6. In a washboard, the combination, with the side bars A and B and top cross-bar C, of the intermediate cross-bar E provided in its upper side with the longitudinal groove a and formed upon one side with the forwardly projecting soap-rest E' having an upper horizontal soap-supporting surface a' projecting forwardly from the base of the brand-board and a rearwardly inclined forward surface terminating at its lower edge in approximately the vertical plane of the upper edge of the front face of the rubbing surface, said soap-rest being provided with a plurality of downwardly and forwardly inclined open drainage notches leading from its upper surface adjacent the base of the brand-board downwardly and forwardly to the upper edge of the front of the rubbing surface, and the brand-board F surrounded by and having its four edges fitting in grooves in the side bars A and B and the top cross-bar C and intermediate cross-bar E, to form a closed-bottom receptacle above the soap-rest E', the drainage from which flows downwardly and forwardly through the inclined open drainage notches and over the rubbing surface of the board; substantially as described.
